UNITED STATES PATENT OFFICE.

PAUL MANSEL, OF BERLIN-CHARLOTTENBURG, GERMANY, ASSIGNOR TO SIEMENS & HALSKE, AKTIENGESELLSCHAFT, OF SIEMENSSTADT, NEAR BERLIN, GERMANY, A CORPORATION OF GERMANY.

MACHINE FOR RECORDING TIME.

Application filed July 5, 1924, Serial No. 724,477, and in Germany June 29, 1923.

- My invention relates to apparatus for checking time of the type which record the time when the workman enters or leaves the works for each individual working day on 5 special printed and cut out cards for each individual workman, said cards being inserted into the apparatus or machine when the workman enters or leaves the works or factory.
- 10 In known apparatus of this type it is necessary to make a special adjustment in order that the record for an entry or exit time value may take place. A mistake in this adjustment renders the whole card useless.
- 15 Furthermore, such apparatus consists of rather complicated mechanism to effect the necessary changes for a different division of the working times, pauses, and the like for the individual days of the week.
- 20 My invention comprises a number of essential improvements in such apparatus or machines and above all eliminates the necessity to make in the card the otherwise customary symbolic perforations for marking 25 the time values. These perforations are according to my invention replaced by printed time value impressions from which by the simple addition of the values corresponding with the time of entry and of leaving the 30 total working time for the week is ascertained. A further object of the improved machine is to allow a quick adjustment of different working conditions, intervals and the like and also to take different working 35 conditions on the individual days of the week into consideration. The improved apparatus is also adapted to properly record the elapsed time where several overlapping working shifts occur and to impress the corresponding working time values without the 40 necessity of making any changes in the apparatus.

In the drawings affixed to this specification and forming part thereof one embodiment of my invention is illustrated by way of example. In them is:

- Fig. 1, a front elevation,
 Fig. 2, a rear elevation,
 Fig. 3, a side elevation of the improved 50 machine,
 Fig. 4, a section along line I—I of Fig. 1,
 Fig. 5, a time card with impressions of time values by way of example,
- Fig. 6, a vertical section of the edge cutting apparatus for the card, 55
 Fig. 7, the printing and cutting device in plan and
 Fig. 8, a section through the counting mechanism along line II—II of Fig. 1.
 Fig. 9 is a partial front view, showing the 60 card adjusting and stamping means,
 Fig. 10 is a lateral section through Fig. 9.
 Fig. 11 is another partial front view, showing especially the devices for arresting the so-called preparation wheels during 65 the setting of the elapsed time recording wheels.
 Fig. 12 is a lateral section through Fig. 11.
 Fig. 13 shows the shaft and the cams by means of which the preparation wheels for 70 the different working shifts are coupled in.
 Fig. 14 is an enlarged view of the type wheels shown in Fig. 1, with the gears associated therewith.
 Fig. 15 is a view similar to Fig. 11, but 75 showing the parts in greater detail, and
 Fig. 16 is a detail view of one of the preparation wheels, with its associated mechanism.
- Referring to the drawings, 1 is the frame 80 of the machine upon the bracket 2 of which a clockwork 3 is attached which may be operated mechanically or electrically and which also serves as the control clock. The clock is connected to the time stamping or 85 printing mechanism 4 in such manner as to maintain the latter in a position to print the exact time as indicated on the dial of the clock. A handle 5 is mounted for limited swinging movement between stops 47 and is 90 normally held against one of said stops by a spring 17. After the work-card 8 is inserted into the funnel 7 by the workman he pulls the handle 5 forward against the other stop. This movement is transmitted by mechanism 95 100 hereinafter described to a hammer head 6, Figs. 4 and 7, which causes the printing mechanism to print the date, hour and minute on the face of the card. The drive of the time printing device is effected in the following manner: The clockwork 3 drives by means of a spindle 9 and gear wheels 10 bevel wheels 11, Fig. 2, whereby a spindle 12 and by means of gear wheels 13, 14, 15 the shaft 16' for the day-time typewheels 4 are 105 turned. One of the day-time typewheels is

keyed upon the shaft 16' while the others ride loosely upon it and are rotated by a driver in a known manner. In line with the shaft 16', but not fastened to it, is arranged 5 a shaft 16, that bears two sets of typewheels for indicating the working hours. These typewheels are not driven directly by the clock work but by means of a driving device, adapted to adjust the typewheels at the time 10 of marking in the position one of several timing wheels has occupied at this time. The day-time typewheels 4 print the date and hour of the day and the working hours typewheels print the working hours elapsed 15 since the beginning of the shift upon the card at the moment the handle 5 is pulled forward.

Upon the type wheel shaft 16' is fixed a gear wheel 18 which consequently rotates 20 together with it and in the example illustrated performs a complete revolution in 10 minutes. This wheel 18 meshes with a gear wheel 20 loose upon the intermediate spindle 19 with which wheel a spring casing 21 and 25 a pinion 22 is coupled. The object of this mechanism is to control the adjustment of preparatory discs 27 in larger hour divisions in spite of the fact that the progress of the time stamping device 4 by the clockwork 3 30 takes place every minute, one of said discs being provided for each of the various working shifts. When the wheel 18 is rotated the casing 21 containing a spring is also rotated and the spring which is fixed at one 35 end to the casing and at the other end to the shaft 19 is set under tension. On the shaft 19 is fixed a whip or double pawl 23 and a pinion 24. The pawl 23 abuts against the teeth of a star wheel 26 fixed upon the spindle 25, which wheel has ten teeth in correspondence with the $\frac{1}{10}$ th hour division chosen in the example of construction so that the pawl cannot rotate freely and the $\frac{1}{10}$ th hour indication can take place. Since 40 the pinion 22 meshes with a gear wheel 28 fixed on the spindle 25 and this wheel performs a complete revolution in one hour the point of the pawl 23 in engagement with the star wheel 26 will recede every 6 minutes 45 from the star wheel and will rotate through an angle of 180° under the action of the said spring 21 so that the other point of the whip or pawl 23 will abut against the next tooth of the star wheel 26. The spring is 50 unwound in this operation by $\frac{1}{2}$ of a revolution and is again wound up by this amount prior to the next release.

With the pinion 24 meshes a gear wheel 29 which is loosely mounted upon the shaft 60 25. Attached to or integral with this wheel 29 is a pinion 30 which meshes with a wheel 31 fixed upon a spindle 33 upon which ride four preparatory wheels 27 or one for each working shift. By the release of the pawl 65 23 which takes place every 6 minutes the

pinion 24 and simultaneously the wheel 29 meshing with it is advanced. Since the wheel 29 is connected by the pinion 30 with the driving wheel 31 the spindle 33 thereupon will be rotated through a small angle. 70 Upon this spindle 33 are fixed toothed driving wheels 34. These driving wheels are housed in recesses of the preparatory wheels 27 as are also locking pawls 35 by the agency of which the preparatory wheels 27 75 are carried around in the direction indicated by the arrow in Fig. 4. On the other hand the wheels 34 may continue to rotate even when the preparatory wheels 27 are held stationary as in this case the locking 80 pawls 35 pass over the teeth of the wheels 34.

Each preparation wheel 27 rotates once during each shift. The beginning and end of each shift is fixed by means of pins 37 on the disc 38, which release the levers 36 and 131 at the beginning of the shift and at the end of any "out" time, such as for lunch. At the end of the shift, pins 37 stop the movement of the corresponding preparation wheel 27. The pins 37 are arranged in groups, each group serving to control one preparation wheel. In this way each preparation wheel is clock-driven, but rotates only during the actual working time of its shift. 95

The arrest of the wheels 27 takes place if a pause as for the lunch hour occurs which should not be counted as working time and in such a case locking levers 36 of which there are four are brought into engagement with the teeth of the wheels 27 by the pins 37 of a disc 38. The said disc 38 is fixed upon the shaft 39 and is rotated by the pinion 40 upon the shaft 12, Figs. 2 and 4, performing a complete revolution during a shift of 12 hours. Upon it are fixed the pins 37 by means of which the wheels 27 are held stationary for a shorter or longer period corresponding with the pause so that the pauses are automatically deducted from the time values. The pins 37 have different lengths and can on both sides of the disc 38 be introduced in two series of holes in such a position and number as corresponds with the time and the length of the pauses. The pins are of different lengths so that each of them cooperates with one of the levers 36 only. The spindle 39 of the disc 38 is adapted to slide in its bearings 42 and can be adjusted by a cam wheel 44 upon a spindle 43 against the side edge of which shaped as broken curve the front edge 46 of the shaft 39 abuts under the action of a spring 45. This axial adjustment of the spindle 39 permits a variation in the combination of pins 37 which control the levers 36 and therefore a control of the elapsed working time for each day of the week. 110

The cam wheel 44 is rigidly secured to a driving star wheel 48. The said star wheel 115

48 is advanced by one tooth during each complete revolution of the disc by a pin 50 upon a disc 49 keyed upon the spindle 39. A bell-crank lever 52 controlled by a spring 53 carries a roller 54, said roller locking the driving star wheel 48 and also the cam wheel 44 secured thereto in position.

The pins 37 of the disc 38 are provided with parts 55, 56 of different diameters.

- 10 The combination of pins is so chosen that the parts 56 of larger diameters operate the levers 36 only at a definite position of the disc 38. The position of the disc 38 is, as explained above, determined by the cam 44.
- 15 Assuming the end 46 of the shaft 39 rests upon a projection of the wheel 44 corresponding with a certain day of the week, the disc 38 and thus the set of pins 37 will also be in a position corresponding with a 20 working time fixed for this certain day. Since the disc 38 rotates continuously a predetermined set of the parts 56 of the pins 37 only will raise the levers 36 while the parts 55 of smaller diameters will move past the levers 36 and not touch them.

Each preparatory wheel 27 is furnished with an abutment 57 with which a pin 58 of the corresponding of four transporting wheels 59 is adapted to come in contact after it has been brought within the reach of the corresponding preparatory wheel 27 by a coupling lever 60 controlled by a spring 66. The adjusting wheels 59 mesh with a pinion 61 fixed upon the type wheel shaft 16 moved by the clockwork mechanism. Fixed upon this shaft 16 are also the unit wheels 62, 63 of two further type wheel sets, said unit wheels divided in $\frac{1}{10}$ th hours being consequently provided with the numbers from 0 to 9. After a complete revolution of these unit wheels the hour wheels 64, 65, upon which the numbers 1 to 12 are inscribed in accordance with the assumed maximum working time of 12 hours within one day, are advanced by one division. The pair of type wheels 63, 65 shown on the left-hand side of Fig. 1 is designed to print the "in" time and is so adjusted that it always will stamp a time lying $\frac{1}{10}$ hour ahead of the real time shown on the control clock 3. This is done to ensure that the workman shall pass in through the gates before the work time commences and be at his station ready to start when the actual working hour strikes. If for example the work commenced at 7 a. m. and the workman stamps his card at exactly 7 a. m., he will lose some minutes on his record card. The type wheel pair 62, 64 for the exit control are so adjusted that they will stamp the true time.

During the control marking, that is during the stamping of the time which has passed during the entry or the leaving of the workman since the beginning of the

shift under consideration only one stamp impression must be applied to the card and only one of the two type wheel sets must come into operation. The control of these stampings is effected automatically by the 70 perforations 67, Fig. 5, provided in the card from the beginning. These perforations are arranged on the card in two vertical rows, the holes in one row being disposed alternately or staggered to those in the other 75 row. During the entry, stamping takes place on the left of the corresponding hole, during the exit at the right of the hole. The perforations are arranged staggered so that the entry and exit values are each arranged in a separate column. The workman is according to the arrangement of the apparatus and the control card obliged and even compelled to stamp his card every time he enters or leaves as irregularities or attempts to cheat will be indicated on his working card.

To effect the stamping two plungers 69 rotatably disposed upon a shaft 68 are provided in the apparatus, Figs. 2, 4 and 7. 80 These plungers or stamps 69 are preferably disposed in such an oblique position that the head 70 of the hammer 71 does not touch them.

After introduction of the control card 8 into the funnel 7 the handle 5 is pulled, causing the pin 150 on the shaft 72 to turn the sleeve 151, which is loosely arranged on the shaft 72. The lower arm of the angular lever or bell crank 73, which is formed integrally with the sleeve 151 is drawn inward against the action of the spring 79, and the upper arm of the same lever releases a pin 74 which is located on a lever 75 loosely mounted on the shaft 39. The lower part of lever 75 will be drawn inward by means of the spring 76 and the upper part of the same lever will be swung outward (rearward) and thereby exert a pull at the springs 77, which are connected to the lower ends of the levers 78, the upper ends of which, as before mentioned, are furnished with plungers or heads 69. These heads are equipped with feelers 79' both of which lie in the same horizontal plane and at a horizontal distance from each other which is the same as that between the two vertical rows of perforations in the card 8. Through the pull at the springs 77 the feelers 79' are moved towards the card 8. As the perforations of the entry and the exit rows are arranged in staggered relation to each other only one perforation will, at any one time, be at the height of the feelers 79'. The continued pull of the springs 77 will bring one of the feelers 79' (the entry feeler or the exit feeler) into the perforation in position, whereupon, the lever 78 on which this individual feeler is located will take up a substantially vertical position and the rearward projection on the head 69 130

will be in position for receiving a blow from the corresponding head 70 of the hammer 71. When so positioned the pad 69' of the head 69 will press the inking ribbon and the card 5 against the elapsed time printer, so that the time of exit or of entrance is recorded on the card. The other feeler 79' will abut against the card and the lever 78 of the same will remain in an inclined position, so that 10 its head 69 will not be operated by the appertaining hand 70 when the hammer 71 is released.

In order to stamp after an entry an exit and after an exit an entry again, the card 15 must at each stamping be cut out to a height corresponding to the vertical distance between two adjacent perforations in the entry and exit row. For this purpose the card is formed beforehand with a recess 83. When 20 a new card for the first time is inserted into the funnel 7 by a workman entering the works the horizontal edge of the recess will abut against a pin 141 on a cutting device 142 and the lowermost entry perforation will 25 be in position for receiving one of the feelers 79'. Simultaneously with the stamping the recess 83 will be lengthened upward in vertical direction by the cutting device 142 actuated by the head 113 of the hammer 71 30 punching out a piece of the card of a length corresponding to the vertical distance between the said lowermost entry perforation and the adjacent lowermost exit perforation. The clippings from the card drop down into 35 a receptacle (not shown) on the base plate of the apparatus through a guide 7'. When now the workman leaves the works and inserts his card 8 into the funnel 7 for stamping, the horizontal edge of the recess 83 will 40 again abut against the pin 141 and the lowermost exit perforation will now be in position for receiving the other feeler 79'.

A correct position of the card during the 45 stamping is further secured by means of the card guide 86 in which the punching device 142 is located and which is shiftably mounted on two guide rods 87. Two springs 88 tend to move the guide 86 to the right-hand side (Fig. 2) of the apparatus until the 50 guide abuts against the vertical edge of the card recess.

For time-checking machines, which are arranged for checking a plurality of overlapping working shifts, different recording cards are used for each shift. In these cards the width of the recess in the cards 8 in a horizontal direction is different for each shift as indicated in dotted lines in Fig. 5. According as the recess in the card is more 55 or less deep in horizontal direction the card guide will, when the handle 5 is pulled, be pressed more or less to the right-hand side of the apparatus (Fig. 2) by the springs 88 before coming into contact with the vertical edge of the card recess and in ac-

cordance herewith the proper one of the preparation wheels 27 for the shift in question will be coupled in by means which will be described below.

When the handle 5 is pulled and the shaft 72 is turned, a lever 89 on the latter will move outward (Fig. 1) and thereby release a pin 90 on a toothed segment 91 (Fig. 1) and thereby release a pin 90 on a toothed segment 91 which is fixed on a shaft 92. On 75 this shaft there is also fixed one of a pair of bevel gears 92, the other bevel gear being fixed on a vertical shaft 94, which by means of a link 95 is connected to the card guide 86. When the pin 90 is released the springs 88 will press the card guide 86 to the left (Fig. 1) and this movement is, through the link 95, the shaft 94, the bevel gears 92 and the toothed segment 91, transmitted to a shaft 97 by means of a pinion 96 thereon. 80 This shaft 97 is equipped with cams 98, by means of which the preparation wheels 27 for each working shift are brought into action. There is one cam 98 for each preparation wheel 27 and its coacting coupling lever 90 85 99. The cams or fingers 98 are all of the same length but point in different radial directions relative to the axis of the shaft 97 (see Fig. 4). It is assumed that a card belonging to the first working shift is inserted 95 into the funnel 7, for example the card shown in Fig. 5 which has a shallow recess in horizontal direction. When the handle 100 5 is pulled and the pin 90 is released, the card guide 86 will only be moved over a very short distance by the springs 88 until it is stopped by coming into contact with the vertical edge of the card recess. The angular movement thereby imparted to the pinion 96 over the toothed segment 91 is 105 a correspondingly small one and only the cam 98 the point of which is lying next up to its appertaining coupling lever 60 (in this example the first cam counting from the right in Fig. 1) is brought into operative 110 position opposite to its coupling lever 60. If the card which is put into the funnel 7 belongs to another working shift and is cut out after the first dashed line to the right 115 on Fig. 5 the card guide 86 will, when the handle 5 is pulled, be pushed over a somewhat longer distance than above mentioned by the springs 88 before the guide comes 120 into contact with the recess. Correspondingly the second cam 98 to the right on Fig. 1 will be swung into operative position opposite to its coupling lever 60 and the first cam to the right will be swung out of operative position relatively to its lever 60. In the same way the remaining two cams 98 125 are set in response to the width of the cards prepared for these working shifts.

During the further movement of the handle 5 an inclined face on a lever 99 on the shaft 72 is pressed against the end of the 130

shaft 97 and presses this to the left side against the force of a spring 84. The cam 98 which at the moment is in operative position will press against a projection 100 on 5 the adjacent coupling lever 60 and carry the lower end of this to the left, whereby the lever will swing about its pivot pin 101 against the force of the spring 66 and by means of its upper forked end 102 will push 10 the sleeve 103 and the transporting wheel 59 fastened upon the same to the right, so that the pin 58 on the wheel 59 is brought into the reach of the pin 57 of the adjacent preparation wheel 27.

15 When the handle 5 is moved still further forwards a toothed segment 104 loosely mounted on the shaft 72 and connected by parallel springs 105 with an arm 106 is also rotated in the direction of the arrow, Fig. 3.

20 The arm 106 is coupled with the spindle 72 by a pin 107 and a recess 108 so that it can be turned in relation to the spindle 72 by a certain angle. The toothed segment 104 meshes with a pinion 109, Fig. 3, which is 25 rigidly attached to or integral with a toothed wheel 110. This wheel meshes with a pinion 111 upon the shaft 16, Fig. 1. The wheels 59 are now by the motion of the handle 5 with the interposed springs 105 turned so 30 far till the previously coupled wheel 59 abuts with its pin 58 against the pin 57 of the corresponding wheel 27. The toothed segment 104 is then arrested and the springs 105 allow the further motion of the handle.

35 By the motion of the toothed segment 104 and that of the pinions 61 fixed upon the shaft 16 the adjustment of the type wheels 62, 64 and 63, 65 is effected for a working shift corresponding with the predetermined 40 wheel 59 and corresponding with the time value which has passed since the beginning of the shift up to the entrance and exit from the works.

The preparation wheels must of course be 45 held in a fixed position during the stamping process. For this purpose a shaft 134 is mounted in the frame and carries the brackets 146 and stopping pawls 138. There is one stopping pawl for each preparation 50 wheel 27 and each pawl is under the influence of a spring 136, which is held in tension by a rod 137, which rod is passed through the apertures in the pawls and through the lever 139, and is supported by the brackets 55 146. The lever 139 is likewise connected to the shaft 134. When the handle 5 is pulled a pin 144 on the lever 99 (which also effects the lateral displacement of the shaft 97) is moved away from the lever 139, which now 60 is drawn inward by the spring 145 and turns the shaft 134, so that the pawls 138 are brought into engagement with the teeth of the wheel 27. The springs 136 provide a more or less resilient connection between 65 the pawls 138 and the wheel 27.

In order to obtain a correct computation of the time values the preparatory wheels 27 must at the beginning of a shift start from a zero position. These wheels perform during a shift fixed at 12 hours a complete 70 revolution. Said wheels are each provided with a stop 130, Figs. 4 and 16, which in the zero position abuts against one of the four locking levers 131, each of which has a recess 131' and is connected with one of 75 the locking levers 36. Both the levers 131 and 36 are actuated by special pins 37 on the disc 38 which correspond with the zero positions of the various preparation wheels 27. Each of pins 37 releases its corresponding locking lever 131 at the beginning of the shift by moving the levers 36 and 131 to the left and bringing the recess 131' in the path of the stop 130 rotating with the preparation wheel 27, allowing the wheel 27 to rotate. Since the simultaneously thrown in locking lever 36 would, however, act retarding a recess 132 is provided at the place in the teeth of the preparatory discs 27 which corresponds with the zero position. 80

The hammer 71 is disposed upon a shaft 112, Fig. 2. It carries upon its upper end four hammer heads, Fig. 7, of which the first, 6, sets the time stamping mechanism 4 (Fig. 14), in operation, the second and third 85 the time value stamps 62, 64 and 63, 65 (in the middle of the card) and the fourth, 113, the cutter 82 (recess 83 of the card). The hammer 71 is controlled by springs 114 which tend to pull it into the working position. A lever 115, Fig. 3, is connected with the frame hammer and cooperates with an abutment or stop 117 fulcrumed upon an arm 116 of the shaft 72 of the handle and controlled by a spring 118. When the handle 5 is moved 90 it sets the hammer under tension and just before it reaches its end position the stop 117 releases the lever 115 of the hammer so that the hammer 71 executes the blow on the stamps by the action of the springs 114. In 95 order that the hammer 71 should not abut against the printing stamps 69 in its withdrawn position and prevent their adjustment it is not moved directly but by means of an interposed piece 119 and abutments 120 provided upon it. Springs 121, Figs. 2 and 4, which are only subjected to a preliminary tension during the blow bring the hammer 71 slightly beyond the reach of the stamp. The motion of the interposed piece 119 is 100 limited on a lever 122 by a stationary abutment 123, Fig. 2.

In order to fix the type wheels 62, 64, and 63, 65 accurately in the printing position for the time value stamping a star wheel 124, Fig. 3, is secured upon their spindle 16. The teeth of said star wheel are engaged by a locking pawl 125 controlled by a spring 126 as soon as during the end motion of the lever 5, after adjustment of the type wheels 125 130

and shortly before the blow of the hammer takes place, a pin 127 provided upon the lever 106 comes up against a double lever 128 controlled by a spring 129. The said lever then releases the stop pawl 125 so that 5 it is free to engage the star wheel 124 and thus to position the shaft 16 of the type wheels correctly.

In apparatus for registering a plurality 10 of overlapping shifts it is advisable to employ a motor drive instead of the hand lever 5, the workman then starting the motor by operating a switch lever when entering or leaving the factory or works, whereupon the motor switches itself automatically off after 15 it has operated the hammer.

The manner of operation of the arrangement is the following:

The clock-work 3 continuously drives the 20 time type wheel 4, the wheels 34 and the disc 38. The preparatory wheel 27 which corresponds with the next shift is secured in its initial position by means of the nose 131 engaging the abutment 130. As the shift 25 starts a pin 37 raises the nose 131 and the preparatory wheel 27 is carried around by the pawl 35 in the direction of the arrow (Fig. 4) rotating synchronously with the clock. As soon as a pause is made in the 30 work another pin 37 raises the pawl 36. The pawl engages the teeth of the preparatory wheel 27 and arrests it for the duration of the pause, this being accomplished by a plurality of pins arranged one behind another 35 or a corresponding flap on the disc 38. After the pause has come to an end the preparatory wheel 27 is released and is again carried around by the pawl 35. The pawl 35 is pressed by a spring 35', which is so strong 40 that the wheel 27 is taken along with the wheel 34 by the frictional engagement between the contact face of the pawl 35 and the tooth face of the wheel 34 only. The pawl 35 engages the wheel 34 in a direction opposite to that of a normal pawl. This 45 arrangement is made because it is necessary that the wheel 34 continue at its rotation in the same direction also during the periods at which the wheel 27 is arrested. Like the 50 pauses the allowances for the entering of the workman are adjusted on the disc 38. The angular movement of the wheel 27 therefore corresponds with the time which has passed since the shift's commencement less the 55 duration of the pauses.

As soon as the workman enters the factory 60 he inserts his card 8 into the funnel 7, whereby the recess in the card will come to rest against the pin 141 of the punching device 82. The workman now pulls the lever 5, the shaft 72 is turned, and the lever 89 is moved outward (Fig. 1), so that the pin 90 on the toothed segment 91 is released. The springs 88 of the punching device 86 will now come 65 into action and push the said punching de-

vice towards the card 8 until it abuts against the vertical side of the card recess 83. This movement of the punching device will actuate the lever 95, the shaft 94 and the bevel gears 93 and swing the toothed segment 91 (Fig. 4). This segment turns the shaft 97 by means of the pinion 96, so that the cam 98 for the working shift in question (responsive to the horizontal width of the card recess 83) is swung up into operative position 70 adjacent one of the levers 60. Simultaneously the lever 99 is swung outward (Fig. 1), and as soon as it comes into engagement with the end of the shaft 97 it will press the same to the left (Fig. 1) against the force 80 of the spring 84, whereby the lever 98, which for the moment is in operative position, by means of the coupling 102, 103, will swing the corresponding wheel 59 to the right, so that its nose 58 is brought into the path of 85 the nose 57 on the preparation wheel 27 belonging to the same set. The pin 144 on the lever 99 will, during the movement of the latter, release the lever 138, while the locking levers 36 are brought into engagement 90 with the wheels 27, which thereby are fixedly held in their position during the stamping.

On the shaft 72 also the two-armed lever 116 is fixed (see Fig. 3), to the upper end of which one end of the spring 17 is fastened, the other end of which is fastened to a bracket in the apparatus. When the handle 5 is pulled, the spring 17 is stretched. The pin 107 on the lever 116 rests loosely in the recess 108 in the lever 106 and will carry 100 this into the same direction as the handle 5 as soon as it (the pin) abuts against the side of the recess. The lever 106 is, like the toothed segment 104, loosely mounted on the shaft 72. As the lever 106 and the 105 toothed segment 104 are interconnected by means of the springs 105, the segment 104, will partake in the movement of the lever 106 and, by means of the gearings 109, 110, 111 and 61, will rotate the shaft 16 and thereby the wheel 59 until the projection 58 of the wheel 59 in operation will abut against the projection 57 on the corresponding preparation wheel 27. The elapsed time 110 type wheels 62-65 thus are set for stamping. As the preparation wheel 27 already 115 at the beginning of the stroke was arrested by the pawl 138 the shaft 16, the toothed segment 104, and the gear train connecting these parts cannot move any further, but the lever 106 continues its movement, thereby further 120 tensioning the springs 105. An exact adjustment of the type wheels 62-65 take 125 place at the end of the stroke when the pin 127 on the lever 106 comes into engagement with the lever 128 and thereby brings the lever 125 into engagement with the star wheel 124, which is fastened on the shaft 16. During the stroke of the lever 5 the pin 150 130 on the shaft 72 which is playing in a slot

in the sleeve 151 will abut against a side face of the slot. The sleeve and the bell crank 73 are turned against the action of the spring 79 and the pin 74 is released. The 5 lower part of the lever 75, on which the pin 74 is located, will thereby be drawn inward and the upper part of the same lever will swing outward and stretch the springs 77, whereby the feelers 79' are moved towards 10 the card. As at the moment of the first entry with a new card only the lowermost perforation of the minus row is in operative position the feeler 79' belonging to the minus row will pass into the said perforation and 15 the head 65 will be in position for receiving a blow from the hammer head 70. At the end of the stroke the spring-actuated stop 117 on the lever 116 will abut against the lever 115, which is rigidly connected to the 20 shaft 112 and slide along the curved face of the same, whereby the lever 115 is pressed backward. Through this movement the interposed piece 119 and the hammer frame 71 on the shaft 121 are spanned against the 25 force of the springs 114. As soon as the stop 117 slides out of engagement with the lever 115 the interposed part 119 and the frame 71 are released, and the upper part of the frame 71 with the heads 6, 70 and 113 30 are forced inward at a very great speed through the action of the springs 114 so that the heads will strike the plungers which are lying in their paths (Fig. 7). At this point the heads 113 operate the card cutting 35 device, the head 6 operates the printing device for printing the day and time, and the left head 70 (the lower head 70 on Fig. 7) operates the cushion 69' belonging to the feeler 79' which is projecting through the 40 lowermost entry perforation of the card, and thus the time is printed on the card and the stamping procedure is completed. It will be understood that at the next stamping operation the lowermost exit perforation 45 will be in position for being engaged by the other feeler, by means of which the exit values of time are stamped on the card. As soon as the stroke of the hammer heads has taken place the frame 71 is automatically 50 moved out of contact with the plungers by means of the springs 121, in which position the frame abuts against the seats 120.

When the workman now releases his hold the handle 5 is drawn back into its original position by the spring 17 causing the shaft 72 to return to its original position. The lever 99 will then slide away from its contact with the end of the shaft 97, so that the latter by the spring 84 is pushed into its normal position. The cam 98, operative at the present stamping operation, is then swung out of engagement with its appertaining coupling lever 60 and the corresponding wheel 59 is brought back into inoperative position and out of connection with the adja-

cent preparation wheel 27. The lever 106 is brought back into initial position by the pin 107 on the lever 116, which pin, as before mentioned, rests loosely in a slot 108 in the lever 106. The pin 127 on the lever 103 now passes out of engagement with the lever 128, which is retracted by its spring 129 and swings the lever 125 out of engagement with the star wheel 124, so that this wheel and consequently the shaft 16 are released. On its way back the pin 127 will engage the toothed segment 104 and bring this into its initial position, whereupon the shaft 16 and the wheels 59 are simultaneously returned to their previous position through 80 actuation of the gear train 104, 109, 110, 111. The lever 115 returns to its original position together with the hammer device since it is rigidly connected to the shaft 112.

As the shaft 72 is moved back during the 85 return movement of the handle 5 the pin 150 is moved out of engagement with the wall of the slot in the sleeve 151, whereupon the lower arm of the bell crank 73 is drawn outwardly by the spring 79 and the pin 74 is pressed downward by the other arm of the bell crank 73 whereby the lower part of the lever 75 is swung outward (to the right in Fig. 4) and the upper part of the same is swung inward, so that the spring 77 is released and the plunger 69 drops down into an inclined position thereby extracting the feeler 79' from the perforation in the card 90. Almost at the end of the return movement 95 of the handle 5 and the shaft 72 the cam 89 abuts against the pin 90 on the toothed segment 91, whereby the latter is swung outward and by means of the bevel gears 93, the shaft 94 and the link 95 imparts a movement to the cutting device whereby this is pushed 100 away from the card 8 against the force of the springs 88. It will be understood, that the apparatus is ready for a new stamping as soon as the handle 5 has returned to its rest position as shown in Fig. 3.

According to the example shown in Fig. 5 the workman entered the factory at 10:20 a. m. and left at 12 p. m. As the working time commenced at 6:00 a. m. and the time is divided into 6 minute-periods the workman starts with a value of 4.4 hours stamped on the left side of the perforations 110 67. When leaving, a value of 6.7 hours will be stamped on the right side of the perforations, so that the wages will have to be settled 115 on the basis of an actual working time of 6.7 minus 4.3 equals 2.3 hours.

As all the described movements take place almost simultaneously the whole stamping procedure, from the insertion to the removal 120 of the card, may be accomplished very quickly by the workman.

It will be readily understood that I do not limit myself to the exact details of construction of the improved working time record- 125 130

ing apparatus and that these may be modified in many ways within the scope of my claims without departing from the spirit of my invention or sacrificing any of its advantages.

What I claim as my invention and desire to secure by Letters Patent is:—

1. The combination in an apparatus for checking time by marking cards, of a card adapted to be introduced into the said apparatus, two parallel rows of perforations arranged in staggered relation in the said card, means for stamping the entry and exit time values on the said card, guiding elements connected to the said stamping means and adapted to cooperate with the said rows of perforations by alternatingly rendering one of the said stamping devices operative, and actuating elements for operating said stamping devices.

2. The combination in an apparatus for checking time by marking cards, of a card adapted to be introduced into the said apparatus, two parallel rows of perforations arranged in staggered relation in the said card, two sets of printing wheels for stamping the entry time values and the exit time values, a pair of stamping devices each of them co-ordinated to one of said sets of printing wheels, a feeler connected to each of the said stamping devices, each feeler being coordinated to one of the said two rows of perforations in the said card, means for alternately bringing one of the said feelers into engagement with a perforation in the appertaining row of perforations and means for pressing the said stamping devices against the card and the printing wheels.

3. A machine for recording the entry and exit time of a plurality of shifts, comprising a card having a recess at its edge, the depth of which corresponds to the shift to be recorded, a clockwork, a set of type wheels driven by said clockwork, a plurality of preparation wheels adjusted by said clockwork, the number of preparation wheels corresponding to the number of shifts, a plurality of driving devices for adjusting the type wheels in accordance with the position of one of said preparation wheels, and means controlled by the depth of the recess in the card for rendering one of said preparation wheels and one of said driving devices operative.

4. A machine for recording the entry and exit time of a plurality of shifts, comprising a card having a recess at its edge, the depth of which corresponds with the shift to be recorded, a clockwork, a set of wheels driven by said clockwork, a plurality of preparation wheels adjusted by said clockwork, the number of said wheels corresponding with the number of shifts, a plurality of driving devices for adjusting said type wheels in accordance with the position of one of said preparation wheels, and means controlled by the depth of the recess in the card for rendering one of said preparation wheels and one of said driving devices operative.

cordance with the position of one of said preparation wheels, an adjustable abutment engaging said recess in said card, a shaft coupled with said abutment, cams upon said shaft, and adjusting devices on the driving devices for the type wheels controlled by said cams in such a manner that according to the adjustment of the abutment in the recess of the card one of the cams renders operative one of said preparation wheels and one of said driving devices.

5. In a machine for recording working time, the combination of type wheels, a preparation wheel, a device for adjusting said type wheels in accordance with the position of said preparation wheel, and means for controlling said type wheels and said adjusting device, said means including a card having a recess at its edge and having two rows of perforations, said rows indicating the entry and exit values respectively.

6. In a machine for recording working time, the combination of type wheels, a preparation wheel, a driving gear for said type wheels, a device for adjusting said type-wheels in accordance with the position of said preparation wheel comprising a continuously rotating member arranged to be intermittently coupled with said preparation wheel, a gearing, a lever, springs connecting the lever with said gearing, a member connecting the preparation wheel with said driving gear, means for controlling said connecting member comprising a card having indicia arranged to indicate respectively the entry and exit values of the recorded working hours.

7. In a machine for recording working time, the combination of type wheels, a preparation wheel, a device for adjusting said type wheels in accordance with the position of said preparation wheel comprising a shaft, a continuously clock driven disc secured to said shaft, said preparation wheel being loosely mounted upon said shaft, a driving wheel for said type wheels axially movable on said shaft, projections upon the driving wheel cooperating with projections on the preparation wheel, and means for controlling said driving wheel comprising a card having indicia arranged to determine the entry and exit value of the recorded working hours.

8. In a machine for recording working time, the combination of type wheels, a preparation wheel, means for adjusting said type wheels in accordance with the position of said preparation wheel, an auxiliary device for stopping the preparation wheel during non-working intervals, comprising a continuously clock-driven disc, projections thereupon, and levers for stopping the preparation wheel, and means for connecting said preparation wheel with the type wheels com-

prising a card having indicia arranged to indicate the entry and exit values of the recorded working hours.

9. In a machine for recording working time, the combination of type wheels, a preparation wheel, means for adjusting said type wheels in accordance with the position of said preparation wheel, an auxiliary control device for stopping the preparation wheel 5 during non-working intervals comprising a continuously clock-driven disc, projections thereupon, another disc for intermittently moving the preparation wheel, locking levers operated by said projections on the 10 clock-driven discs, gearing upon the preparation wheel cooperating with the locking lever, means for connecting said preparation wheel with the type wheels comprising a card having indicia arranged to determine 15 the entry and exit values of the recorded working hours.

10. In a machine for recording the working time of a plurality of shifts, the combination of type wheels, a preparation 25 wheel, a device for adjusting said type wheels in accordance with the position of said preparation wheel, an auxiliary device and a ratchet cooperating to control said first mentioned device, said auxiliary device 30 comprising a stop upon the preparation wheel and a lever for stopping the preparation wheel during the time between the end of one shift and the beginning of the next shift in the position corresponding with the 35 zero position of the type wheels, means for connecting said preparation wheel with the

type wheels comprising a card having cut out portions, some of said cut out portions being arranged to determine the entry and exit values of the recorded working hours. 40

11. In a machine for recording working time, the combination of a perforated card, type wheels being adapted to print on said card, a preparation wheel, a hammer movable toward said card, means for adjusting 45 said type wheels in accordance with the position of said preparation wheel, and means for controlling said type wheels and their adjusting means comprising levers, feelers upon the levers for selectively bringing one 50 of the levers into operative position between the hammer and the card opposite one of the type wheels by cooperating with corresponding perforations in the card.

12. In a machine for recording working 55 time of a plurality of shifts, the combination of type wheels, a plurality of preparation wheels, one for each of the several shifts, means for adjusting said type wheels in accordance with the position of said preparation wheels comprising a plurality 60 of clock-driven gear wheels and driving wheels for the type wheels, means for connecting said driving wheels with the corresponding preparation wheels comprising a 65 card having perforations arranged to indicate the entry and exit values of the recorded working hours and the shift in which the hours were worked.

In testimony whereof I affix my signature. 70

PAUL MANSEL.
